Specification for Design.

Patented Jan. 31, 1911.

Application filed July 16, 1910. Serial No. 572,387. Term of patent 14 years.

To all whom it may concern:

Be it known that I, EMMA R. LEE THAYER, a citizen of the United States, and resident of Hastings-on-the-Hudson, county of Westchester, State of New York, have invented a new, original, and ornamental Design for Cartons, of which the following is a specification.

Reference is to be had to the accompanying drawings in which—

Figures 1 and 2 are perspective views looking at different sides of a carton showing my new design.

The design comprises a carton having adjacent panels or sides on one of which is centrally produced a fleur de lis and four

smaller fleurs de lis to each side and above and below said central fleur de lis. An ornamental border comprising scroll work and beads extends about said panel at the edge thereof and surrounds said fleur de lis. A similar border is similarly produced on the adjacent vertical side or panel of said carton and incloses a substantially elliptical blank shield.

I claim:

The ornamental design for a carton as shown and described.
